UNITED STATES PATENT OFFICE.

TAYLOR W. HEINTZELMAN AND JAMES G. CAMP, OF SACRAMENTO, CALIFORNIA.

AIR-FEEDING APPLIANCE FOR OIL-BURNING STEAM-BOILER FURNACES.

No. 861,515.

Specification of Letters Patent.

Patented July 30, 1907.

Application filed November 6, 1906. Serial No. 341,967.

To all whom it may concern:

Be it known that we, TAYLOR W. HEINTZELMAN and JAMES G. CAMP, both of Sacramento, in the county of Sacramento and State of California, have jointly invented a certain new and useful Improvement in Air-Feeding Appliances for Oil-Burning Steam-Boiler Furnaces, of which improvement the following is a specification.

Our present invention relates more particularly to, 10 and is an improvement in, oil burning apparatus of the general character of that set forth in Letters Patent of the United States No. 830,833, granted and issued to us under date of September 14, 1906, and its object is to provide means, of simple and inexpensive construction and ready applicability in connection with fireboxes of the ordinary type, whereby the supply of air at the rear of the firebox may be conveniently and accurately regulated in accordance with the conditions of combustion, the angle of deflection of the 15 incoming air adjusted as required, and enginemen and firemen protected from danger of injury by "flashing" in the event of an over supply of oil to the burner.

The improvement claimed is hereinafter fully set forth.

25 In the accompanying drawings: Figure 1 is a front view, in elevation, of an air feeding appliance embodying our invention; Fig. 2, a horizontal section through the frame and the adjoining portion of the hood; Fig. 3, a side view of the hood, detached; Fig. 30 4, a bottom view of the same and of the connected damper; Fig. 5, a vertical longitudinal section through the appliance complete, and through the adjoining portion of the rear water wall of a steam boiler firebox to which it is attached; and, Fig. 6, a plan or top view 35 of the deflecting plate.

Our improved air feeding appliance, is, similarly to that set forth in our Letters Patent No. 830,833 aforesaid, herein shown as connected to the rear water wall, 3, of the firebox of a tubular steam boiler, and as 40 adapted to control the supply of air thereto through an upper air supply passage, 24, formed in said rear water wall, and to change the direction of the current of air supplied through said passage, by a deflecting plate, 27. The structural features of improvement 45 in an air feeding appliance of the above general type which constitute our present invention will now be described.

In the practice of our invention, we provide a frame, 24^a, which corresponds substantially in contour with the upper air supply passage, 24, and is secured by bolts or rivets, in the ordinary manner, to the rear water wall, 3, of the firebox, surrounding and forming an outward extension of the passage, 24. This 50 passage may either be one specially formed in the rear water wall, or in application to a steam boiler designed for, or previously used with solid fuel, it may

be the ordinary door opening. An air feeding hood, 25, which is open at its front and bottom, and closed at its top, sides, and back, and which has its rear wall outwardly inclined, is connected to the frame, 24^a, 60 preferably, as shown, by being hinged thereto, the hood, in such case, being provided with lugs, 28, on one side, through which and through lugs, 24^b, on the frame, a hinge pin, 29, passes, and with a lug, 28^a, on its opposite side, through which passes a pin, 30, fixed to the frame, the hood being held up to the frame by any suitable fastening, as a key, 31, fitting in the pin 30. An opening, 32, is formed in the rear wall of the hood, said opening being normally closed by a cover plate, 33, suspended on a pin, 34, fixed in the 70 rear wall of the hood. The cover plate is held in position by a spring, 35, surrounding the pin and subject to adjustment as to tension by nuts, 36, engaging a screw thread thereon. By swinging the cover plate on the pin, 34, the opening, 32, may be uncovered 75 when desired, for the purpose of introducing sand into the firebox to free the tubes from deposits of carbonaceous matter.

The area for the passage of air through the open bottom of the hood, 25, and thence to and through the upper air supply passage, 24, is controlled and varied as required by a damper or regulator, 26, fitting in the bottom opening of the hood, and pivotally connected to the hood, so as to close said opening, either completely or to any desired degree less than complete 80 closure. The damper is pivoted to the hood by pins 26^a; 26^b, passing through lugs, 25^a, on the lower ends of the side walls of the hood, and fixed in lugs, 26^c, on the lower side of the damper, one of the pins, as 26^a, being turned upwardly, to form an operating handle, 90 by which the damper may be swung upon the common axis of the pins, to effect its desired adjustment, and the other, as 26^b, being threaded and provided with a nut, 26^c, by which the damper may be clamped and held in position when adjusted, with the capacity of 95 ready variation therefrom as desired.

A baffle or deflecting plate, 27, the function of which is to deflect the current of air entering the firebox through the upper air supply passage, 24, downwardly towards the burner, is connected to the frame, 24^a, and 100 extends therefrom, in downwardly inclined position, through the passage, 24, into the firebox. The deflecting plate is preferably provided with downwardly turned lateral lips or flanges, 27^a, as shown in Fig. 5, and its forward portion, or that projecting into the 105 firebox, is perforated by a plurality of openings, 27^b, said openings permitting a portion of the entering air to pass through the deflecting plate, thereby preventing it from being rapidly burned out. The deflecting plate is supported on the frame, 24^a, by lateral bearing 110 pins, 27^c, at its rear end, which rest in sockets in the frame, and is held in position by a substantially verti-

cal stop arm, $27^{\frac{1}{2}}$, formed on one of said pins, and having a chipping piece, $27^{\frac{1}{2}}l$, which abuts against the frame. The proper angle of the deflecting plate may generally be determined with substantial accuracy, 5 and variation or adjustment thereof in operation is not necessary. If, however, it should be found desirable to vary the angle of the deflecting plate, owing to changes of conditions of fuel or other causes, this may readily be done by cutting off a portion of the chipping piece, $27^{\frac{1}{2}}l$, or by inserting a liner between its end and the frame, as the case may be.

The open bottomed hood and the adjustable damper controlling the lower opening thereof, are essential and characteristic features of our invention which have 15 been found, in practical and continued service, to be of substantial advantage. The closed rear wall of the hood serves to deflect flame caused by flashing under an excessive supply of oil, downwardly on the deck of the locomotive, and thereby protects the engineman 20 and fireman from injury by the horizontal discharge of the flame which would otherwise occur. This wall, with its opening and cover plate, also provides convenient means for sanding the tubes when required.

The location of the damper, and its pivotal connection to the bottoms of the side walls of the hood, are such as 25 to enable its control of the entering current of air, and its adjustment for variation of the amount of air admitted, to be effectively exerted and readily manipulated.

We claim as our invention and desire to secure by 30 Letters Patent:

The combination with a steam boiler fire box having an upper air supply passage, of a frame connected to the fire box wall and surrounding said passage, an air feed hood removably connected to said frame and closed at its top, 35 sides, and rear, the bottom thereof being open, an adjustable damper connected to said hood and controlling the open bottom thereof, said rear wall provided with a sand supply opening, a cover plate controlling said opening, a deflecting plate having a plurality of perforations in its 40 forward portion and fitting at its rear in the frame and projecting forwardly and downwardly through the air supply passage and means for adjusting the inclination of the deflecting plate.

TAYLOR W. HEINTZELMAN.
JAMES G. CAMP.
